BURNER FOR FLUID FUEL

Edward L. Torrey, Oakland, Calif.

Application September 30, 1940, Serial No. 358,951

12 Claims. (Cl. 158—63)

The invention relates to a fluid-fuel burner particularly designed for use in the heating of air and other fluids.

An object of the invention is to provide for an efficient production of heat from the combustion of the so-called "low-grade" fuel oils, and particularly mineral oils.

Another object is to provide a burner in which the complete gasification of all combustible fractions of a fuel oil is assured.

A further object is to provide a combined generator and burner having means operable to prevent the accumulation of free carbon thereupon.

Yet another object is to provide a fully and uniformly oxygenated gaseous mixture for feeding the fire of the burner.

A still further object is to provide a burner which is operable in whole or in part with fuel gases generated externally thereto.

The invention possesses other objects and features of advantage, some of which, with the foregoing, will be set forth or be apparent in the following description of a typical embodiment thereof, and in the accompanying drawings, in which,

Figure 1 is a perspective view showing the burner of my invention in use as part of an air-heating unit, portions of the structure being broken away.

Figures 2 and 3 are sections of the burner taken respectively at the lines 2—2 and 3—3 in Figure 5.

Figure 4 is a fragmentary perspective view of a scraper element of the burner.

Figure 5 is an enlarged vertical axial section through the burner assembly.

Figure 6 is a side view of the fuel-vaporizing portion of the burner.

Figure 7 is a fragmentary view at the line 7—7 in Figure 6.

Figure 8 is a horizontal plan view at the line 8—8 in Figure 6.

As particularly illustrated, a burner unit embodying the present features of the invention is disclosed as being operatively installed in an air-heating furnace 12 which essentially comprises a casing 13 providing an air-heating space 14 surrounding a combustion chamber 15 comprising a member 16 having end walls 17 and a continuous side wall 18, and supported on legs 20 extending from its bottom. The burner 11 extends through and from the end walls 17 in sealed relation thereto and is supported thereby. A flue pipe 19 extends from an upper point of the casing 16 through and from the space 14 of the casing 13 for the external discharge of combustion products from the combustion chamber 15. As particularly shown, the combustion chamber casing 16 is of "tear-drop" cross-section of the general form shown in my Patent Number 1,981,378 which issued on Nov. 20, 1934, and provides a particu-

larly efficient heat exchange from its interior and through its walls to air in the space 14, through which space air is arranged to be circulated by convection in a usual and well-known manner, the heated air escaping at one or more openings 21 provided at the top of the furnace casing. The air to be heated is admitted at a lower point of the casing 13, which casing may be provided with suitable baffles (not shown) for directing the incoming air against the combustion chamber walls 17 and 18 for its heating.

The burner unit 11 includes a tubular shell 22 which has its ends extended through flanged openings 23 at opposite ends of the furnace casing, the axis of the shell being horizontal. By particular reference to Figures 1 to 3, it will be seen that the shell 22 has a general "air foil" cross-section with its trailing edge uppermost in conformity with the disposal of the casing 16. At its lower side, the shell 22 is provided with an opening which extends longitudinally of the shell between points which lie inwardly of its points of sealed engagement with the ends 17 of the combustion chamber casing 16; the side edges or lips 24 of said shell opening lie in a horizontal plane below the widest part of the shell. It will be noted that the shell bore preferably tapers somewhat from its center in both horizontal and vertical section to compensate for the heating of the air which enters from both ends of the air tunnel provided by the shell 22. Also, the walls of the shell 22 are thickest centrally of the length of the shell.

An elongated pan member 26 depends from the shell 22 with its cavity below and opposite the bottom shell opening defined by the lips 24, and has its ends notched to closely receive the tubular shell ends 25. Ears 27 extend horizontally from the shell 22, and the pan 26 is bolted to and beneath said ears; as shown, the pan 26 is formed with mutually coplanar side flanges 28 receiving bolts 29 which secure the pan to the shell. The pan 29 is arranged to function as a drip pan and priming cup with respect to the burner assembly, and the plane of its rim defined at the flanges 28 is disposed above the plane of the shell opening and is laterally spaced from the opposed shell walls. To facilitate combustion in the pan 26, the sides and bottom thereof may be lined with a metallic mesh overlaid with asbestos as is indicated.

The gas-generating elements of the burner are supported by and between the tubular end portions 25 of the shell 22 and essentially comprise an assembly of elongated pans aligned in a common vertical plane and from which unevaporated liquid fuel may descend gravitally until evaporated to provide gases for burning, it being recalled that mineral fuel oils are made up of fractions which evaporate at different tempera-

tures. Essentially, the elements of the gas-generating assembly comprise upper and lower members 31 and 32 respectively which cooperatively define a cavity 33 in which a plurality of bubble trays are mounted; two trays 34 and 35 are shown. The members 31 and 32 comprise intermediate trough-like portions providing the upper and lower parts of the cavity 33, said portions extending inwardly and between the ends of the pan 26 and having stem extensions 36 and 37 respectively.

The stems 37 of the member 32 rest upon adjustment screws 38 which extend from the bottom of the sleeve ends 25 for use in levelling and vertically adjusting the tray assembly within the combustion chamber 15. The member 31 is fixedly mounted upon spacing blocks 39 provided at the ends of the stems 37 of the member 32, and is fixed in place by means of tension bolts 40 operative at and between the inner ends of the stems. Preferably, and as shown, the portions of the bolts 40 nearest their heads are slidably engaged in longitudinal slots of corresponding stems and are threadedly engaged in the other stem. The spacing blocks 39 are preferably formed of a slightly compressible material such as asbestos, and are compressedly held in place between the stem extremities by the tightening of the bolts. The arrangement is designed to provide for relative longitudinal expansions of the members 31 and 32 without buckling or strain, such expansions arising from the high and possibly different temperatures to which they are subject during the functioning of the burner.

It will be particularly noted that the bottom and top edges of the members 31 and 32 respectively are spaced to cooperatively define slits 42 substantially in the plane of the bottom opening defined by the lips 24 of the shell 22, and through which gas escapes from the cavity 33 for its combustion along the outer face of the shell. The members 31 and 32 are notched upwardly and downwardly from the plane of the slits 42 and solely at the ends of the cavity 33 to provide air inlets 41; said notches 41 of the member 32 also function to limit the liquid capacity of the basin provided by the member.

The bubble trays 34 and 35 are similar, and are mounted in horizontal position within the members 31 and 32 respectively. The extremities of the tray 34 are secured to downwardly facing seats at the ends of the cavity of the member 31 by screw bolts 43, and bolts 43 also secure the extremities of the tray 35 to upwardly facing seats provided at the ends of the cavity of the member 32, said trays being spaced from the plane of the slits 42 at opposite sides thereof. A line of liquid overflow outlets 44 is provided in and along the tray bottoms and in bosses 45 which extend from the tray bottoms to planes slightly below those of the tray rims. The outlets 44 of the trays 34 and 35 are in mutually staggered relation whereby liquid overflowing from the tray 34 through an outlet 44 may not fall directly into an outlet of the underlying tray 35. The bottom of the member 32 receives and retains the overflow from the tray 35 up to a level determined by the bottoms of the end notches 41 of the member.

Means are provided in the member 31 for admitting both fluid fuel and air to the cavity 33. Centrally thereof, and at its top, a fuel pipe 46 is connected to the member 31 for the drip discharge of liquid fuel upon the upper tray 34, said pipe extending through the shell 22 from one

end thereof. The liquid fuel is delivered to the pipe 46 by gravity from a suitable drip valve 47 of a supply pipe 48 and through an elbow 49 having a plate 50 at its end perforated around the valve nozzle which engages it. The pipe 46 is provided with a dam 51 within it and at its lower end whereby it may retain a small amount of liquid fuel to the dam level for overflow into an elbow 52 as the liquid is supplied through the valve 47; the present dam 51 is provided as an annular constriction at the discharge end of the pipe bore, and the constant retention of some liquid fuel in the pipe behind the dam provides for a preheating thereof before the fuel falls into the upper tray 34.

A circle of holes 53 is provided axially through the boss portion 54 of the member 31 which receives the down-turned discharge end of the elbow 52, and upright slots 55 extend longitudinally through the member 31 from the boss 54 to both ends of the cavity 33; the holes 53 and slots 55 provide passages for the flow of air from the shell 22 into the cavity 33. As will hereinafter be brought out, the operation of the present burner creates a suction in the pipe 46, and such suction is relieved in part by the induction of air through the air inlet openings at the top of the elbow 49, through the holes 53, through the slots 55, and through the notches 41 in the ends of the members 31 and 32 which cooperatively provide the gas-generating space 33.

Recalling that the underlying pan 26 is open along opposite sides of the shell 22, it will now be noted that a preliminary combustion of liquid fuel in said pan is arranged to heat up the described gas generating elements for the generation of gaseous fuel from the liquid therein. Accordingly, an initial charge of priming fuel is arranged to be placed in said pan through a pipe 56 entering one end or by an overflow of liquid fuel from the member 32. As indicated in Figure 5, the pipe 56 extends through the front of the furnace casing 13 and the member 16 to its connection in the pan end, and its outer end is provided with an upturned funnel 57 from which it slopes slightly to its discharge end within the pan. The top of the funnel 57 is below the level of the pan rim whereby an overflow return of liquid is permitted for limiting the amount of the priming charge, priming liquid being supplied to the funnel 57 from a valved drip pipe 58. A constant flow of liquid fuel through the pipe 56 may be provided to supply a constantly lit pilot flame within the pan and at the inner end of the pipe 56 which may be provided with a jet nozzle.

When the priming liquid in the pan 26 is burning, the gas-generating elements are heated for the generation of gasified fuel and its discharge through the slits 42 for its combustion, it being noted that the combustion of the priming charge and generated gases induces a convection flow of air into and through the cavity 33 and from the slits with the gasified fuel whereby a zone of combustion is provided against the outside of the shell. In this manner, the combustion is arranged to take place upwardly along the sides of the shell 22, the supply of gaseous fuel being automatically generated and maintained after the priming charge has been consumed.

The present burner assembly is adapted for the efficient burning of gaseous fuel which has been generated outside of the burner, such gaseous fuel being supplied to and through the burner supply pipe 46. While pre-generated gaseous fuel might be supplied through the pipe 48, it is pre-

ferred to independently supply any gaseous fuel at the elbow 49. Preferably, and as shown, a gas pipe 59 is connected to the elbow 49 and terminates in a nozzle 61 which is directed axially of the pipe 48 for discharging thereinto; in this manner, liquid and gaseous fuels may be introduced together into the burner in any desired proportion. It will be understood that the present burner may be operated entirely with a pre-generated gas, in which case only the evaporation operation at the trays 34 and 35 is omitted in the operation of the burner which also acts as a gas-air mixer; the arrangement is understood to provide for utilizing liquid and/or gaseous fuels as they are available and without requiring any changes or adjustments of the burner parts for any change-over.

Means are provided for preventing an undesirable accumulation of carbon or scales on the surfaces of the members 31 and 32 at and adjacent the slits 42. As shown, a rod 63 is reciprocably engaged between the members 31 and 32 in the plane of the tray outlets 44, and carries scraper assemblies 64 providing scraper blades for operation along certain surfaces of the members. The assemblies 64 are mounted at equally spaced points along the rod 63 and generally within the cavity 33, and the permitted working strokes for said assemblies at least equals their mutual spacing whereby to permit a complete scraping of the surfaces to be operated on. One end of the rod 63 extends from the burner assembly, and means are provided for effecting an operative reciprocation and control of the rod; as particularly illustrated, a knob 65 is fixed on the extending rod end for use in manually reciprocating the rod, it being understood that an intermittently operative mechanical means might be provided for the purpose.

Referring particularly to Figures 2 to 5 inclusive, it will be noted that the scraper assemblies 64 include arms 66 extending radially from hubs 67 fixed on the rod 63, and freely through the slits 42. Blades 68 extend upwardly from the arms 66 for engagement with and along the adjacent inner wall faces of the member 31, and similar blades 69 depend from the arm for engaging with and along inner face portions of the member 32. Blades 71 depend from the outer ends of the arms 66 for operative engagement with and along the outer side faces of the member 32 below the slits 42, and it will be understood that each arm portion between the inner and outer blades thereon is arranged to function as a scraper blade in the slits. The various blades 68 and 69 and 71 may lightly and resiliently engage the surfaces which they are to clean, and the rod 63 is loosely engaged in and between the stem portions 36 and 37 of the members 31 and 32 respectively whereby the necessary freedom is provided for lateral and rotary and axial movements of the scraper assembly. In this manner, full operative applications of the scraper unit may be effected by actuations of the rod 63 while the burner is in operation.

It will now be noted that the disclosed disposal of the rod 63 in a vertical plane through the overflow outlets of the upper bubble tray 34 will effect a splashing distribution of liquid fuel falling upon it to thereby direct some of the liquid upon the side walls of the cavity 33 to facilitate the vaporizing process, any unevaporated liquid flowing along the cavity walls to the tray provided by the bottom of the lower member 32 for its evaporation thereat; this functioning of

the rod 63 is understood to be independent of its use as a mounting for the scraper assemblies 64. Since the vaporization of the liquid fuel is facilitated by increasing the exposure of its surfaces to heat, the splashing of the liquid fuel upon all surfaces of and within the cavity 33 is essential to a maximum efficiency of vaporization. Also, it will be understood that the number and arrangement of bubble trays within the cavity may be varied to the same end, and that no limitation is to be implied as to the particularly disclosed arrangement.

Means are provided for insuring a thorough mixing of the gaseous discharge from the slits 42 with air received directly from the shell 22 and before the mixture reaches the combustion zone along the outside of the shell, it being noted that the intake of air through the openings 53 and 55 provided therefor at the top of the generator member 31 does not provide all of the oxygen needed to support the combustion of the gaseous fuel. As particularly shown, rod-like members 72 are mounted in the general plane of the slits 42 in the shell space between the assembly 31-32 and the bottom rims of the shell, the baffle rods 72 being shown as carried on suitable brackets 73 mounted on the member 31.

In burning gaseous fuel emitted from the slits 42, a particular disposal of the slits with respect to the common plane of the shell lips 24 will be necessary for the best operation of the burner with a particular fuel, and the screws 38 which support the generator assembly are utilized for providing any adjustment which may be needed, this being accomplished without dismantling the generator and while the burner is in use. At normal burning conditions, the base of the fire is outwardly of and along the shell lips 24, yet the fire base may extend to the outer sides of the slits 42 under low-fire conditions; in either event, the flow stream of the gaseous fuel mixture and combustion products is between said lips and creates a desirable turbulent flow of air through the shell bore to complete the necessary combustion-supporting air supply to the fire.

From the foregoing description taken in connection with the accompanying drawings, the advantages of the construction and operation of the present burner will be readily understood by those skilled in the art to which this invention appertains. While I have described the features and principles of operation of an assembly which I now consider to comprise a preferred embodiment of my invention, I desire to have it understood that the showing is primarily illustrative, and that such changes may be made, when desired, as fall within the scope of the following claims.

I claim:

- 60 1. A fluid fuel burner comprising a member arranged for its heating and providing an elongated cavity therein having its longitudinal axis horizontal and having air and fuel inlets and a side outlet for the discharge of the gaseous mixture resulting from the mixing of the inlet air and fuel, said outlet comprising an horizontal slit, and an open-ended tubular shell enclosing said member longitudinally of said slit in spaced relation from the member and provided with a bottom opening having its upper edge disposed substantially in the same horizontal plane with the slit and arranged for the passage of the said gaseous mixture beneath said edge for its combustion along the outer shell surface.
- 65 2. A structure in accordance with claim 1 hav-
- 70
- 75
- 78

ing means adjustable to vertically adjust the position of the member in the shell.

3. A structure in accordance with claim 1 whereof the shell is of air-foil form with its trailing edge extending upwardly.

4. In a liquid fuel burner, a down-draft vaporizer comprising a hollow member arranged for its heating by the combustion of vaporized fuel discharged therefrom and providing a horizontally elongated cavity therein having an air inlet slot along its top and a vapor outlet slot along its side and a fuel inlet, a scraper blade engaged in said vapor outlet slot, and a means for actuating said scraper to clean the slot during the operation of the burner.

5. In a liquid fuel burner, a down-draft vaporizer comprising a hollow member arranged for its heating by the combustion of vaporized fuel discharged therefrom and providing a horizontally elongated cavity therein having an air inlet slot along its top and a vapor outlet slot along its side and a fuel inlet, and a means operable to clean the surfaces of the member at and adjacent the vapor outlet slot while the burner is in use.

6. In a liquid fuel burner, a vaporizer comprising a member arranged for its heating and providing an elongated cavity therein having its longitudinal axis horizontal and provided with a side vapor outlet and an air inlet and a liquid-fuel inlet, said member comprising a pair of mutually opposed elements which extend from a horizontal plane through the vapor outlet and are unitarily secured together by means which permit their relative expansions in directions parallel to said plane, means to continuously supply liquid fuel to and through said fuel inlet, and means to utilize the fuel vapors issuing from the vapor outlet to supply a fire which is arranged for heating the member for the continued generation of fuel vapors therein.

7. In a liquid fuel burner, a down-draft vaporizer comprising a hollow member arranged for its heating by the combustion of vaporized fuel discharged therefrom and providing a horizontally elongated cavity therein having an air inlet slot along its top and a vapor outlet slot along its side and a fuel inlet, the side wall of the cavity providing an evaporation surface for wetting by the liquid fuel, and means within the cavity operative to distribute the received liquid fuel upon and along said evaporation surface adjacent said vapor outlet slot.

8. In a liquid fuel burner, a vaporizer comprising a hollow member arranged for its heating by the combustion of vaporized fuel discharged therefrom and providing a horizontally elongated cavity therein having an air inlet slot along its top and a vapor outlet slot along its side and a fuel inlet, the side wall of the cavity providing an evaporation surface for wetting by the liquid fuel, an evaporation tray disposed in the cavity longitudinally thereof and in spaced relation from the cavity sides and arranged for the free overflow fall of liquid therefrom, and a deflector means operative upon the liquid falling from the tray to distribute the liquid upon the cavity side wall above and below the vapor outlet slot for its evaporation from said wall.

9. In a liquid fuel burner, a vaporizer comprising a hollow member arranged for its heating by the combustion of vaporized fuel discharged

therefrom and providing a horizontally elongated cavity therein having an air inlet at its top and a vapor outlet slot along its side and a fuel inlet, an evaporation tray disposed in the cavity longitudinally thereof and in spaced relation from the cavity sides to receive liquid fuel from said fuel inlet and arranged for the free overflow fall of liquid therefrom in a line therealong, and a baffle element disposed in the path of liquid falling from the tray to deflect liquid upon the cavity side wall adjacent the vapor outlet slot for evaporation from said wall.

10. A fluid fuel burner comprising a member arranged for its heating and providing an elongated cavity therein having its longitudinal axis horizontal and having air and fuel inlets and a side outlet for the discharge of the gaseous mixture resulting from the mixing of the inlet air and fuel, said outlet comprising a horizontal slit, an open-ended tubular shell enclosing said member longitudinally of said slit in spaced relation from the member and provided with a bottom opening having its upper edge disposed substantially in the same horizontal plane with the slit and arranged for the passage of the said gaseous mixture beneath said edge for its combustion along the outer shell surface, and a baffle means interposed in the path of discharge of the gaseous mixture from the outlet slit and inwardly of said shell edge for facilitating the mixing of air from within the shell with the gaseous mixture from the slit.

11. A fluid fuel burner comprising a member arranged for its heating and providing an elongated cavity therein having its longitudinal axis horizontal and having air and fuel inlets and a horizontal side outlet slit for the discharge of the gaseous mixture resulting from the mixing of the inlet air and fuel, an open-ended tubular shell enclosing said member longitudinally of said slit in spaced relation from the member and provided with a bottom opening having its upper edge disposed substantially in the same horizontal plane with the slit and arranged for the passage of the said gaseous mixture beneath said edge for its combustion along the outer shell surface, and a baffle means interposed in the path of discharge of the gaseous mixture from the outlet slit and inwardly of said shell edge for facilitating the mixing of air from within the shell with the gaseous mixture from the slit.

12. In a heater, a fluid fuel burner comprising a member providing an elongated cavity therein having its longitudinal axis horizontal and having air and fuel inlets and a horizontal side outlet slit for the discharge of the gaseous mixture resulting from the mixing of the inlet air and fuel, an open-ended tubular shell enclosing said member longitudinally of said slit in spaced relation from the member and provided with a bottom opening having its upper edge disposed substantially in the same horizontal plane with the slit and arranged for the passage of the said gaseous mixture beneath said edge for its combustion along the outer shell surface, and a casing providing a combustion chamber and fittedly receiving the shell through it and across its chamber to provide for the entry of air into the chamber entirely through the shell and provided with a discharge outlet for the escape of combustion products therefrom.

EDWARD L. TORREY.
